ERNST ELIAS BRAND, OF HALSINGBORG, SWEDEN.

CHANNEL-FURNACE.

1,291,748.

Specification of Letters Patent. Patented Jan. 21, 1919.

Application filed January 19, 1918. Serial No. 212,583.

To all whom it may concern:

Be it known that I, ERNST ELIAS BRAND, a subject of the King of Sweden, residing at Raus Plantering, Helsingborg, Sweden, have invented new and useful Improvements in Channel-Furnaces, of which the following is a specification.

The object of the present invention is an arrangement of channel furnaces in such a manner that the heat of the goods treated in them can be utilized at the cooling, which is of importance, as the said goods contain very great quantities of heat, which hitherto are lost.

As known, a channel furnace as a rule contains three compartments: the pre-heating chamber, in which the material is pre-heated by combustion gases from the next chamber, the combustion chamber, and the cooling chamber, in which the heated material meets and is cooled by a cold air current, which passes to the combustion chamber in which it contributes to the combustion.

Experiments have proved that the said air, passing through the cooling chamber, moves itself almost horizontally without any essential variations in a vertical direction and that it for that reason cannot come in any such intimate contact with the material to be cooled that the heat of the said material can be taken up completely or almost completely by the air. Such a complete utilization of the heat of the material to be cooled cannot be obtained by extending the channel furnace, so that a longer cooling chamber is obtained, in which the contact between the air and the material becomes longer, because the extension of the furnace in such a case should be so large that the furnace would not be economic.

According to the present invention the object aimed at may be reached by arranging in the roof or the walls of the cooling chamber passed by combustion air directly from the delivering end of the furnace and above the bottom of the trucks supporting the material treated, a number of openings, communicating with a device for forcing air currents into the chamber in an an-

gle to the current of combustion air, above 50 mentioned. By this arrangement this latter current of combustion air is given such a movement that it is brought into an intimate contact with the burnt material and can take up a large part of its heat. 55

In the accompanying drawing the delivering end of a channel furnace according to the present invention is illustrated schematically in a vertical longitudinal section.

a is the furnace, and *b* the trucks for the 60 material. According to the invention there are arranged in the roof or the walls of the furnace openings *c*, through which air, by means of for instance a ventilator, is forced into the upper channel of the furnace and 65 thereby produces a movement in the air passing from the delivering end through that channel, so that the said air is brought into an intimate contact with the material, the heat of which thereby is taken up very com- 70 pletely by the air.

The openings for the introduction of air, as already mentioned, may be arranged in the walls of the furnace as well as in its roof, and their number is of no importance, as the 75 object is only the forcing into the furnace of air currents in an angle to the air current, passing from the delivering end of the furnace, and to bring it in such a movement that it obtains a more complete contact with the goods than heretofore. 80

Having now particularly described the nature of my invention and the manner of its operation, what I claim is:

1. A furnace having a channel for the reception of material to be cooled, means for creating a draft horizontally through said channel, and means for creating air currents downwardly of said channel so as to cause the same to intercept the horizontal 85 draft at right angles whereby the horizontal draft is forced downwardly and into intimate contact with the material to be cooled. 90

2. A furnace having a channel for the reception of material to be cooled, means for creating a draft horizontally through said channel, the upper wall of said channel being 95 formed with openings, an air-supply pipe

communicating with all of the openings in the upper wall and means for creating an air current downwardly in said pipe where-
by air currents will be supplied to said
channel to force the horizontal draft into
intimate contact with the material to be
cooled.

In testimony whereof I have signed my name to this specification in the presence of two subscribing witnesses.

ERNST ELIAS BRAND.
